UNITED STATES PATENT OFFICE.

SAMUEL F. NEWMAN AND JAMES G. HARPER, OF WAYNESBORO, PENNSYLVANIA, AS
SIGNORS TO LANDIS MACHINE COMPANY, OF WAYNESBORO, PENNSYLVANIA, A
CORPORATION OF PENNSYLVANIA.

DIE HEAD.

Application filed August 10, 1922. Serial No. 580,972.

Our said invention relates to an improved die head of the stationary automatic type for cutting threads on bolts, pipe and the like, the general features being somewhat similar to what is shown in the patent to Miller 1,296,546, March 4, 1919. It is an object of the invention to provide an improved means for holding the parts of the head together and in position on a shank 5 adapted to be fixed in a chuck of ordinary type.

Another object of the invention is to provide an improved cutter holding means.

Another object is to provide improved 15 means for indicating the relative adjustment of the body and shank and still another is to provide improved means for excluding dirt from the inside of the head.

Referring to the accompanying drawings 20 which are made a part hereof and on which similar reference characters indicate similar parts,

Figure 1 is a face view of the device,

Figure 2 a section on line 2-2 of Figure 25 1, and

Figure 3, a side elevation of the co-operating flanges and rings showing the graduations.

In the drawings 10 indicates a shank 30 adapted to be held in place by the ordinary chuck used in machines of this type, this shank having a concentric forwardly-extending flange 11. A ring 12 located in front of said flange is fixed for longitudinal 35 yielding movement relative thereto by spring-pressed screws 13 similar to those shown in Figure 4 of the patent above referred to. The ring is held against rotation relative to the flange by a pair of pins 14 and 15 secured in any convenient manner to 40 the flange. Another ring 16 is located in advance of the ring 12 and this ring is connected to the cutter holding blocks 17 by any convenient means to open and close 45 the cutter jaws by a rotative movement of the ring on the body 18. Rings 12 and 16 with flanges 11 form a ring frame for said body. The pins 14 and 15 may have reduced portions 19 extending into bushings 50 20 for holding the ring 16 in a position cor-

responding to the closed position of the jaws, as in our co-pending application No. 580,210 of even date herewith, until said ring and the body shall have been moved longitudinally away from the shank and the 55 ring 12 in the manner customary in machines of this type and these extensions may be reduced at opposite sides as in said application.

The body 18 has bores extending from end 60 to end thereof to receive the trunnions 21 which in this case are integral with the cutter holding blocks 17. Midway of their lengths the bores are formed with inwardly extending flanges 22 for receiving the reduced ends of the trunnions, which are threaded beyond the flanges and carry lock nuts 23 and 24, by means of which the trunnions may be set so as to move with sufficient freedom, but without undue looseness, 70 under the influence of the usual springs 25. In automatic die heads of the smaller sizes, a spring such as is shown in our application No. 580,210 of even date herewith is preferably used for opening the head, in place of 75 that here shown.

As will be understood the body 18 is movable longitudinally with the ring 16 in the releasing movement of said ring and for this purpose it has a flange 26 at the forward 80 or outer end, and an annular recess at its inner or rear end to receive a collar 27 with segmental inturned flanges or lugs 32 and 33 engaging recesses at the inner end of the body. This collar is fixed to the body in 85 any convenient manner (not shown) and forms spacing means between the body and the inner side of the flange on the shank, lugs 33 at the same time providing convenient means for retaining the springs 25 90 in position. At its forward end the collar 27 bears against a ring 28 having a rearwardly extending flange in a recess of the flange 11, the two flanges adjacent their meeting edges being graduated as shown in 95 Fig. 3.

The head body 18 is located concentrically with the flange 11 and is held in place by the ring 12 through the medium of screws 13 and springs surrounding them and bearing 100

against the lower ends of recesses in the flange as in the patent above referred to. The ring 12 acts through ring 28 against the collar 27 fixed to the head body to prevent relative longitudinal movement between these parts. Thus it will be seen that the head body with the parts carried thereby and rings 12, 16 and 28, forms a unit which moves forward away from the flange 10 in opening the head, the ring 16 also having rotary movement on the body after the longitudinal movement is completed. Pin 31 engages ring 28 on collar 27 to drive one from the other. Any convenient adjusting means may be provided for rotating the body slightly relative to the ring 16 to vary the diameter of the space enclosed by the cutters, one such means being shown in our above mentioned co-pending application of even date herewith. A flange 29 is provided on the shank to engage the interior of the body and provide an additional bearing therefor. This flange forms an inner guard to exclude dirt or metal shavings from the space back of the head and the bores therein, and ring 28 provides an outer guard for the same purpose, the flange also serving as a centering member if desired. A pin 30 on the body engages a laterally elongated opening in the ring 16 to limit the oscillation of the ring as it moves to open and close the head.

In the present embodiment of our invention we have shown the blocks 17 as adapted to hold longitudinally grooved tangential cutters or chasers 34 of the well-known Landis type, though some features of our invention are adapted for use with cutters of other varieties. It will be obvious to those skilled in the art that various changes may be made in the device above disclosed without departing from the spirit of the invention, the true scope of which is indicated in the appended claims.

Having thus fully described our said invention, what we claim as new and desire to secure by Letters Patent, is:

1. A die head having a shank, a ring frame extending forwardly therefrom said ring frame including a ring movable longitudinally of the head, a head body within said ring, a flange on said head body engaging the forward end of said ring, a separate collar at the rear end of said head body engaging the rear end of said ring frame to prevent relative longitudinal movement between the head body and the ring frame, trunnions supported in said body, cutter holders on said trunnions, and means for moving said cutter holders outward comprising springs arranged in bores in said body said collar having flanges to hold said springs in place, substantially as set forth.

2. A die head comprising a body, supporting means therefor surrounding the body

and comprising means movable longitudinally with the body, a collar at the rear end of the body engaging said longitudinally movable means, cutters on the body movable to open and closed positions, and means for opening said head including springs mounted in longitudinal bores on said body said collar having flanges to hold said springs in place, substantially as set forth. 70

3. A die head comprising a hollow body having longitudinal bores, trunnions mounted in some of said bores and having cutter holders integral therewith, a ring surrounding the head body and adapted to oscillate thereabout to open and close the head, springs in other bores connected to said ring to open the head, a shank having concentric flanges located respectively within and about the body, a pair of rings between the outer flange and said first-named ring the body and the rings being movable toward and from the shank and the rearmost ring having a flange, and a collar on the body bearing against the rearmost ring and cooperating with the flange thereof and the inner flange on the shank to exclude dirt from the interior of the head said collar also having a flange for holding said springs in place, substantially as set forth. 75 80 85 90

4. In a die head, a body having longitudinal bores, supporting means therefor, cutter-holders pivoted in certain of said bores, means to secure said cutter holders in place in said bores, springs in other bores, a ring about the body rotatable relatively thereto and adapted to be moved by said springs for opening the head, and a collar engaging a portion of said supporting means to prevent longitudinal movement of the body relative to such portion said collar having means for engaging said springs to hold them in place and leaving the cutter-holder supporting bores free, substantially as set forth. 95 100 105

5. In a cutter head, a shank having a radial flange, a head body movable axially away from said shank, longitudinally-serialized tangential cutters on the head body, an oscillatory ring on the head body for moving the cutters into and out of working position, a second ring on the head body, pins carried by the shank for locking said oscillatory ring said pins fitting closely in bearings in said second ring, a third ring uniform in diameter with said flange and the other rings said third ring being secured to the body for axial and rotatable movement therewith relatively to the shank, a flange on said third ring overlapping a reduced portion of the flange on said shank, 110 115 120 125 and graduations on adjacent peripheral faces of said relatively rotatable flanges for indicating the operative size of the head, substantially as set forth.

6. In a die head, a body having longitudi- 120

nal bores, chasers on said body, springs in
said bores for moving the chasers out of
operative position, and a ring secured to the
body said ring having projections extend-
5 ing over said bores at one end thereof to
hold said springs in place, substantially as
set forth.

In witness whereof, we have hereunto set
our hands at Waynesboro, Pennsylvania
this twenty-ninth day of July, A. D. nine-
teen hundred and twenty-two. ¹⁰
